UNITED STATES PATENT OFFICE.

ROBERT A. BECKER, OF POUGHKEEPSIE, NEW YORK, ASSIGNOR TO CHARLES TREMAIN,
OF POUGHKEEPSIE, NEW YORK.

T, Y, AND L CONNECTOR.

1,345,982.

Specification of Letters Patent.

Patented July 6, 1920.

Application filed November 27, 1916. Serial No. 133,632.

To all whom it may concern:

Be it known that I, ROBERT A. BECKER, a citizen of the United States, residing at Poughkeepsie, in the county of Dutchess 5 and State of New York, have invented certain new and useful Improvements in T, Y, and L Connectors, of which the following is a specification.

The object of this invention is to provide 10 a device for more efficiently connecting electrical conductors and cables in mechanical construction work, particularly in the shapes commonly known as T's, Y's, L's, and the like.

15 And a further object is to provide in such devices an arrangement whereby the respective gripping members in being clamped into place bind directly against each other, or one another, as the case may 20 be, or are separated only by a washer or other means to lessen the friction therebetween.

Further details of the construction and operation of the device are hereinafter fully 25 brought out in the following specification when read in conjunction with the accompanying drawings, in which Figure 1 is an elevational view of a T connector embodying the invention; Fig. 2 is a vertical, longitudinal section of the same; Fig. 3 is a vertical, transverse view of the same; Fig. 4 is an elevational view of an L connector embodying the invention; Fig. 5 is a vertical, longitudinal sectional view of the same; 30 Fig. 6 is an elevational view of a Y connector embodying the invention; and Fig. 7 is a vertical longitudinal sectional view of the same.

Referring particularly to Figs. 1 to 3, a 40 substantially T-shaped hollow casing 20 is shown as provided with a longitudinally extending bore 21 and a transverse intersecting bore 22, each internally threaded and adapted to receive interchangeable plugs 23, 45 provided in turn with central outwardly tapering bores 24.

Situated within each of the alined plugs 23 is a gripping member comprising a body portion 25 and spaced, tapering, yielding 50 fingers 26, coöperating with the inner tapering bore of the respective adjacent plug to contract said fingers about the bared portion of a conductor or other member 27, as the plug is screwed into place. A gripping member 28, similar to that described, but

recessed at 29 in its body portion, is located within the laterally projecting plug, said recess permitting said member to partially encircle the others of said members and thus insure a solid uniform contact between them. 60

As shown in Fig. 2, a washer 31 may be placed between said alined gripping members to decrease the friction between them, if they tend to turn with the plugs. The third or laterally projecting gripping member 65 engages directly against the sides of the others of said members, tending to create a firm unyielding joint, capable of carrying as heavy a current as the adjacent wires without any possibility of heating.

The L connector shown in Figs. 4 and 5 comprises an angular casing 35, having a bore 36 and an angularly extending bore 37, each being internally threaded and receiving a centrally bored plug 38, in which is located a gripping member 39, similar to those hereinbefore described. One of these members is shorter than the other and when in place bears firmly against the side of the other of said members, or against a transverse partition, and partially surrounding the latter, if desired. Thus, the conductors 40 or other members are secured together in a very firm engagement, which effectively prevents all heating in the connector, or possibility of the joint becoming unintentionally loosened. 80

In the instance of the Y connector, Figs. 6 and 7, a casing 45 is provided, having three angularly positioned bores 46, either 90 of the same or of different diameters, in the outer ends of which are normally screwed plugs 47, having central tapering bores 48, in which are situated similar gripping members 49. Said last-named members preferably have positioned between them bushings, two of which 50 are beveled at 51, while the third 52 has converging surfaces 53 against which the beveled surfaces of the other bushings are forced, as the respective 95 plugs are screwed into place.

Having thus described my invention, what I claim and desire to protect by Letters Patent of the United States is:—

A connector, comprising a casing having 105 a bore, an outwardly tapering gripping member within said bore, a contracting member having a tapered bore and adapted to be screwed in said casing and contract the tapered end portion of said gripping mem- 110

ber extending into said last-named bore, and a second bore within said casing opening into said first bore, the axis of said casing bores being angularly disposed with respect to each other, an outwardly tapering gripping member within said last-named bore, and a second contracting member having a tapered bore and adapted to be screwed upon said casing and contract the end portion of 10 said second gripping member extending into

the bore of said second member, by forcing one gripping member directly against a laterally directed face portion of the other gripping member.

In testimony whereof I have affixed my 15 signature in presence of two witnesses.

ROBERT A. BECKER
